UNITED STATES PATENT OFFICE.

GEORGE J. ARENDS AND JOHN J. ARENDS, OF ROCK RAPIDS, IOWA.

LUBRICATOR-PUMP.

No. 927,923.

Specification of Letters Patent.

Patented July 13, 1909.

Application filed May 6, 1908. Serial No. 431,117.

To all whom it may concern:

Be it known that we, GEORGE J. ARENDS and JOHN J. ARENDS, both citizens of the United States, and residents of Rock Rapids, in the county of Lyon and State of Iowa, have invented a new and Improved Lubricator-Pump, of which the following is a full, clear, and exact description.

Our invention relates to improvements in lubricator pumps, and particularly to such as are employed in the cylinder lubrication of heat engines, in which a reciprocating plunger, playing in an oil pumping cylinder, operates in conjunction with a kinematic element of the engine; and the objects of our improvements are first, to assure continuity in the oil feed to the pump; second, to afford facilities for the necessary preheating of the oil to be delivered to the pump; and, third, to provide expedients in the regulation of the oil delivery.

We attain the objects by the mechanism illustrated in the accompanying drawings, in which—

Figure 1 is a side elevational view of our lubricator pump, showing the same as applied to the cylinder of a horizontal steam engine; Fig. 2 is an enlarged sectional elevational view of the lubricator pump taken through the oil reservoir and certain parts of the pump and valve mechanism and delivery outlet; Fig. 3 is a rear side elevational view of the same on the same scale as that of the preceding view; Fig. 4 is a sectional elevational view of the same taken on the line 4—4 of Fig. 2, in the direction indicated by the arrow; and Fig. 5 is a cross sectional view of the same taken on the line 5—5 of Fig. 2, in the direction indicated by the arrow.

Similar characters of reference designate like parts throughout the several views.

B is the oil supply reservoir for the lubricator, which has an integrally formed head *h* having a central externally counterbored perforation for the reception of a vertical steam pipe *b*. It is fitted by a screw thread to a lower centrally and similarly perforated cap *1^B*, having an internally threaded integral outlet nipple *4^B*. The steam pipe *b* passes likewise through the perforated cap *1^B*, and is packed at *9^B* at the upper extremity of the reservoir B and at the lower end thereof. The lower packing is designated as *1ⁿ* and is forced into the counterbored perforation and similarly

against the pipe *b*, by the adjacent end face of a coupling *n* screw-threaded to the terminal of the said pipe. The office of the steam pipe *b* thus disposed, is to supply heat to the lubricating oil contained in the reservoir B, as will be more fully hereinafter explained.

To the upper terminal of the steam pipe *b* is fitted an "ell" *B⁹*, to the outlet of which is fitted a nipple *B'*, carrying a union *B²*, and a nipple *B³*, to which is fitted an "ell" *B⁴* carrying a steam inlet pipe *B⁵*, the lower terminal *B⁸* of which is obliquely formed, presenting an elliptical contour for the ingress of steam. Adjacent to the terminal *B⁸* and formed exteriorly on the steam inlet pipe *B⁵*, is a screw thread *B⁶* which, when the lubricator is in operation and connected up to a steam engine as in Fig. 1, taps radially the way *P* of the throttle valve *V* of the engine. The lower sections of piping comprise the nipple *1^b*, screw-threaded to the coupling *n*, carrying and fitted to the "tee" *2^b*, having a neck *4^b*. From the tee *2^b* depends the threaded nipple *3^b*, fitted to the "ell" *5^b*, the latter carrying a horizontal pipe *6^b*, to the terminal of which is screw-threaded an upright portion in alinement with the depending inlet pipe *B⁵*. This consists of an "ell" *7^b* screw-threaded to the terminal of the pipe *6^b*, trued up for the reception of a long nipple *8^b*, to which is threaded a nut *9^b*, a union *b'*, an internally threaded flanged nipple *b²*, and a flanged branch *b³* having an oil spout *b⁶* having a tapering external nipple thread *b⁷* which taps the valve way *P* of the valve *V*, and diametrically opposite the inlet pipe at the nipple threaded portion *B⁶* is coupled with the union nipple *b²*, which as well as the union is made steam tight by the gaskets *b⁴* and *b⁵* respectively. The spout *b⁶* is choke bored and is bent at its terminal *b⁸* to direct the delivery laterally.

The disposition of the piping just described provides in effect a rectangular loop, and when a draft of steam is directed toward the engine cylinder and valve chest A via the valve way *P*, a portion will be scooped up the pipe *B⁵*, through the elliptical opening *B⁸* of the inlet *B⁷*, and shunted around said pipe loop and emerge from the spout *b⁶*, passing along with the current of steam via the way *P* to the engine. The effect of the steam loop circulation, thus effected, will obviate condensation as well as

maintain a continual supply of heat for the pipe *b*, wherewith to heat the oil in the reservoir *B*, in order that its viscosity may be reduced to a sufficient degree to facilitate 5 its being pumped by the injector mechanism through the spout *b*^g of the pipe loop, to the engine.

The pumping mechanism of the lubricator consists primarily of the pump cylinders *C* 10 and *d* set at right angles to each other and which lie in the same plane, and, respectively, perpendicularly and horizontally disposed within the pipe loop and adjacent to the reservoir *B* and pipe *b*^g respectively. The

15 cylinder *C* is carried in the outlet nipple *4*^b of the lower cap *1*^b of the reservoir *B*, by a straight away needle valve casing *8*^b; this latter has an integrally formed branch nipple *5*^b, externally threaded, which is engaged 20 with and secured in the outlet nipple *4*^b. The latter is faced off on the end and opposes a plane annular shoulder *7*^b similarly formed around the base of the nipple *5*^b, and between these two faces, carried by the nipple *5*^b, is a packing ring *3*^b, to effect a tight joint thereat. A packing ring *2*^b is similarly disposed between the lower terminal of the 25 reservoir *B* and the seat of the cap *1*^b.

The bore *8*^c of the valve casing *8*^b, has a 30 threaded counterboring *9*^c at its upper end, into which is screw threaded the lower terminal of the pump cylinder *C* and the cylinder *C* is bored in common with the bore *8*^c. Within the bore of the cylinder *C* and adapted 35 to vertically reciprocate therein, is a cylindrical plunger piston *3*^c provided with an elongated concentrically disposed extension or stem *4*^c. The piston *3*^c is of sufficient length to make a stroke vertically downward in the cylinder *C* and the bore *8*^c of the valve casing *8*^b, and project to some extent beyond the upper terminal of the said cylinder. The upper terminal of the cylinder *C* is made fluid tight with the piston *3*^c, by 40 a stuffing box *1*^c, screw-threaded thereto, and a gasket *2*^c.

The lower terminal of the bore *8*^c of the valve casing *8*^b has a neck *C'* which is counterbored at its lower terminal to form a 45 ball valve seat *C*², into which is thrust by a spiral spring *C*³ a ball valve *C*⁴. The lower terminal *C'* of the valve casing *8*^b, is concentrically counterbored with the bore *8*^c and neck *C'* to reach the seat *C*², and is internally 50 threaded to receive a bushing *C*⁵, which carries an oil drip spout *i*. The upper terminal of the bushing *C*⁵ serves as a pedestal for supporting the lower extremity of the valve spring *C*³. The terminal *C'* of the 55 valve casing *8*^b is externally threaded to fit an internally threaded union coupling *C*⁶ to which is coupled by a flanged head, the casing *C*⁹ of a sight glass *C*⁸. Resting upon the upper terminal of this casing and 60 jammed fluid tight with and against the

upper end of the glass *C*⁸ and the annular surface of the terminal *C'* of the valve casing *8*^b by the union coupling *C*⁶, is an annular, centrally perforated gasket *1*ⁱ through which the oil spout *i* is thrust. The casing *C*⁹ is internally screw-threaded at its lower terminal, and has lateral windows *D* through which the glass *C*⁸ and its contents may be seen.

The horizontal pump, comprises a cylinder *d*⁷⁵ similar to the cylinder *C*; and is carried by the neck *4*^b of the tee fitting *2*^b, the nipple *8*^b screw-threaded thereto, and the tee fitting *6*^b screwed thereto, carrying the cylinder *d* similarly secured. The tee fitting *6*^b has its branch nipple presented vertically to the casing *C*⁹ and is screw-threaded into the adjacent terminal thereof and carries on its annular face a packing ring *1*^b which affords a fluid tight union thereat with the lower 80 terminal of the sight glass *C*⁸. The tee fitting *6*^b has a branch bore *7*^b common with the bore of the cylinder *d*, and a vertical bore *2*^b coincident with that of the bore of the glass *C*⁸. The cylinder *d* is provided with a piston *9*^b, stuffing box *1*^d and packing ring *2*^d disposed relatively as already described in connection with the corresponding parts for the cylinder *C*. The piston *9*^b has a stem *3*^d similar to that of the stem *4*^c of the piston *3*^c 95. The bore *7*^b of the fitting *6*^b terminates in an annular neck *j*, which is counterbored at its outer terminal to seat a ball valve *5*^b by a thrust spring *1*^b pocketed in a counterbored tubular bushing *4*^b. 100

The control of the oil feed from the supply reservoir *B*, is effected by a tee-handled needle valve *1*^s (Fig. 5), which is screw-threaded in the branch outlet *3*^b of the casing *8*^b and made fluid tight by a packed stuffing box *2*^s. Toward the inner terminal of the needle valve *1*^s and angularly branching therefrom to a cylindrical surface, is a port *6*^b, which terminates at the opposite extremity at the entrance to the nipple *5*^b. 110 The conical terminal of the needle valve *1*^s has a corresponding seat in a lateral inlet to the bore *8*^c, which will be apparent by reference to Fig. 5. The port *6*^b is adapted to establish communication with the bore *8*^c 115 when the needle valve *1*^s is backed off sufficiently to uncover it. In Fig. 5, the needle valve *1*^s is shown closed and the oil feed from the reservoir *B* to the pumps is cut off.

The driving mechanism for the vertical 120 and horizontal pumps just described, is carried by an **S** bracket *6*^d screwed at one of its terminals to the lower cap *1*^b of the reservoir *B* and depending therefrom. The terminals of the **S** bracket *6*^d present substantially, when the same is positioned as illustrated, upper and lower oppositely directed arms, the latter of which is perforated and carries a tight fitting tubular bearing *S*³, provided with a flat surfaced 125

head d^7 , through which is thrust a spindle S^4 carrying at its inner extremity a ratcheted crank disk 7^a , provided with a hub S^2 and at its outer extremity a crank handle d^6 . The spindle S^4 and the crank handle are fitted in telescoping relation and are secured together by a cotter bolt S^6 . To the ratcheted crank disk 7^a , is secured a crank pin S and to this are fitted in bearing relation, the two driving extremities of each of the pump connecting rods 7^c and 5^d , and an intervening bearing washer W . The stem 4^c of the piston 3^c carries a set screwed adjustable collar 5^c having an integrally formed and radially extending arm or wrist pin 6^c , from which is terminally swung by the driven extremity, the connecting rod 7^c which is held against lateral displacement by a cap screw in a familiar manner. The connecting rod 5^d is likewise swung on the wrist pin 2^d of a similar collar 4^d secured to the stem 3^d of the piston 9^p . Swung upon the hub S^2 of the ratcheted crank disk 7^a , is a concentric strap S' carrying a depending lever d^5 to which is swung upon a stud d^2 , a spring pressed pawl d' engaging the teeth of the ratcheted disk 7^a . Carried and secured to the depending lever d^5 is an extension bar I , the upper terminal of which is bent flatwise at right angles and upon this bent portion is secured the stationary terminal of a spring d^3 for the pawl d' carried by the lever d^5 ; and swung upon a stud 9^d , secured thereto adjacent to the ratchet wheel 7^a , is a counter pawl 8^d , which falls upon the perimeter of the ratchet teeth of the wheel 7^a and checks any tendency to backlash or reverse motion on the part of the spindle S^4 .

When the lubricator thus described, is in position and connected to a steam engine A, as illustrated in Fig. 1, the extension bar I is connected by a pitman H to the valve stem E of the engine, by means of a yoke F secured thereto, and a vertically swinging rocker G hung by a bracket from the framework of the engine.

The reservoir B of the lubricator has integral with its head h an inlet tap e , the upturned end 1^e of which is threaded and into which is screwed a threaded plug 2^e , having a head and gripping lug 3^e .

The operation of the pump is effected by first charging the reservoir with a supply of cylinder oil through the uncapped inlet tap e , then capping it by means of the screw plug 2^e ; then opening the needle valve; next turning the spindle S^4 by the crank handle d^6 , which will drive both the vertical and horizontal pumps, and by observing through the sight glass C^s whether the oil is being forced past this point through the spout i as desired, whereupon the required adjustment of the needle valve will be ascertained.

The feeding of the oil referred to, is effected through the rotation of the disk 7^a , driven

upon starting by the ratchet mechanism or crank handle just described, which drives the vertical and horizontal pump pistons, and as the oil in feeding past the needle valve 1^s by gravitation, reaches the bore 8^c of the cylinder C , the piston 3^c forces it, on its downward stroke, to open the ball valve C^s , and pass thereby through the spout i via the sight glass C^s to the bore 7^p of the cylinder d . In the meanwhile, the piston 9^p following the stroke of the piston 3^c at 90° , will force the oil past the spring-seated valve 5^p and the oil will circulate with the steam draft down and around the lower piping through the perforated bushing 4^p , nipple 3^b , "ell" 5^b , horizontal pipe 6^b , up the "ell" 7^b , to the vertical pipe 8^b and discharging oil spout b^e into the valve chest A and cylinder of the engine.

Having thus described our invention, we claim as new and desire to secure by Letters Patent:

1. In a lubricator, an oil reservoir, a steam loop passing through the reservoir, oil pumping mechanism communicating with the steam loop, a deflecting inlet terminal for the steam loop, and a second substantially opposite terminal for the same, carrying a spout.

2. In a lubricator, an oil reservoir, a system of steam piping, a portion of the said system being enveloped by the oil reservoir, pumping mechanism connected respectively with the oil reservoir and the system of steam piping, a valve therebetween, and an inlet and an outlet in the system of steam piping respectively for steam and oil.

3. In a lubricator of the character described, an oil reservoir, a system of piping having a terminal inlet member, and a terminal outlet member, pumping mechanism connected with the reservoir and the system of piping, and valves controlling communication between the reservoir and said piping.

4. In a lubricator of the character described, an oil supply reservoir, a system of piping having a terminal member provided with an oil delivery spout, the said piping having a second deflecting inlet terminal, and a pump connected to the reservoir and piping and adapted to control the communication therebetween.

5. In a lubricator of the character described, an oil reservoir, a system of piping, a pair of pumps arranged at right angles to each other and communicating, one of said pumps being connected with the reservoir and discharging into the other pump, and the last mentioned pump discharging into said piping, and a common driving member for the said pumps.

6. In a pumping lubricator of the character described, the combination with a system of piping having an inlet for steam and an outlet for oil, oil pumps and an oil res-

ervoir, a part of said piping being disposed within the oil reservoir and forming a heater for the same, of a valve controlled connection between the reservoir and the oil pumps 5 and a valve controlled connection between the pumps and piping.

7. In a pumping lubricator of the character described, the combination of an oil reservoir, and a pipe loop having opposing 10 terminals, of pumping mechanism between the reservoir and pipe loop for feeding oil within said pipe loop and forcing it from one of said terminals, and means for controlling the said oil feed.

15 8. In a pumping lubricator of the character described, an oil reservoir, a pipe loop passing through the reservoir, oil feeding and ejecting pumps connecting the reservoir and pipe loop, an oil spout carried by a 20 terminal of the loop, a steam inlet carried by another terminal of the loop, and means for controlling the feed and ejection of the oil.

9. In a lubricator, an oil supply reservoir, 25 a substantially rectangular pipe loop having a vertical member extending through the reservoir, the said pipe loop having an inlet terminal for steam connected with the upper end of said vertical member, and an outlet 30 terminal for oil connected with the lower end of said vertical member, the inlet and outlet ends of said pipe loop being located adjacent to each other, a vertically arranged oil pump connected with the lower end of 35 said oil reservoir, and a horizontally arranged pump connected with the pipe loop below the reservoir and adapted to receive oil from the first pump, and force it into the said pipe loop, and means for driving the 40 said pumps.

10. In a lubricator, an oil reservoir, a steam pipe loop having a member passing through the reservoir, oil pumping mechanism communicating with the reservoir and with the said pipe loop, the said loop having 45 an inlet terminal beveled at the end presenting an elliptical contour, and an outlet terminal for oil arranged opposite the said inlet and provided with a spout having a bent end.

50 11. In a lubricator, an oil reservoir, a steam pipe loop having a member passing through the oil reservoir, the said loop having an inlet for steam and an outlet for oil, a valve casing having a bore communicating 55 with the reservoir, a needle valve for controlling the oil feed from the reservoir, a vertically arranged pump having its cylinder communicating at its lower end with the bore of the valve casing, an oil drip spout carried at the lower end of the valve casing, a spring pressed valve in the casing for controlling the passage of oil to the oil drip spout, a horizontally arranged pump communicating with the pipe loop, a spring 60 pressed valve controlling said communication, and a sight glass between the said valve casing and the horizontal pump and communicating at its lower end with the cylinder of said pump, the said oil drip spout 65 opening into the upper end of said sight glass.

In testimony whereof we have signed our names to this specification in the presence of two subscribing witnesses.
